UNITED STATES PATENT OFFICE.

GIDEON G. OWEN, OF HOUSTON, OHIO.

GRAVE-VAULT.

SPECIFICATION forming part of Letters Patent No. 606,230, dated June 28, 1898.

Application filed May 27, 1897. Serial No. 638,437. (No model.)

To all whom it may concern:

Be it known that I, GIDEON G. OWEN, a citizen of the United States, residing at Houston, in the county of Shelby and State of Ohio, have 5 invented a new and useful Grave-Vault, of which the following is a specification.

My invention relates to the construction of grave-vaults, coffins, and similar articles; and the object in view is to provide a simple construction of sectional receptacle which when the parts are assembled is water and air tight, and, furthermore, to provide means whereby a vault constructed in accordance with my invention may be used as a casket and interiorly draped in a manner similar to caskets and coffins.

Further objects and advantages of this invention will appear in the following description, and the novel features thereof will be 20 particularly pointed out in the appended claim.

In the drawings, Figure 1 is a perspective view of a vault constructed in accordance with my invention. Fig. 2 is a similar view 25 with the top removed. Fig. 3 is a longitudinal section. Fig. 4 is a perspective view of the top inverted. Fig. 5 is a detail view of the bottom. Fig. 6 is a detail horizontal section of one corner of the receptacle.

Similar numerals of reference indicate corresponding parts in all the figures of the drawings.

As above indicated, the construction embodying my invention is adapted to be applied to either vaults or caskets or to any similar receptacles, the material employed being asphalt or concrete, comprising Portland cement and crushed stone, or being any similar suitable composition adapted to be 40 molded.

In the drawings I have illustrated a receptacle adapted for use either as a vault or as a casket, according to dimensions, but particularly adapted for use as a casket independently of any other receptacle.

1 designates the base, provided with an elevated central portion 2 and a depressed edge portion 3, the shape and dimensions of said elevated portion corresponding accurately 45 with the interior plan of the receptacle and having beveled corners 4, for a purpose hereinafter explained. The side and end walls 5

and 6 rest upon the depressed edge portions of the floor or bottom of the receptacle, the end walls abutting terminally against the flat 55 inner end surfaces of the side walls, and said side and end walls are in contact at their inner surfaces with the edges of the raised central portion of the base or floor, as shown in Fig. 3. The side walls are provided with integral corner-braces 7 of cross-sectionally-triangular construction, of which the outer ends are abrupt to bear against the inner surfaces of the end walls, while the beveled inner surfaces correspond with the beveled or cut-away corners 4 of the raised central portion 60 of the base. Hence these triangular enlargements or braces 7 not only bear against and support the end walls, but form a broader 65 base for the side walls and secure an interlocking connection between the side walls and the base, which adds to the general strength of the structure. The depressed portion of the base is provided with a cement-groove 8, in which "slush" cement is adapted 70 to be arranged prior to arranging the side and end walls in their operative positions, and the contiguous contacting surfaces of the side and end walls are provided with corresponding registering grooves 9 and 10, in which cement 75 is adapted to be deposited after said side and end walls have been arranged in their proper relative positions. The cement which is introduced into the registering grooves in the inner surfaces of the side walls and the contiguous end surfaces of the end walls after 80 it has become hardened forms a key which effectually prevents the relative displacement of the members of the receptacle. In the same way the upper edges of the side and end walls are provided with cement-grooves 11 and 12, which are adapted to be filled prior 85 to disposing the top or cover 13 upon the upper edges of said wall, the proper course to pursue being to fill said grooves 11 and 12 to overflowing, or so as to cause the cement to project slightly above the edge surfaces of the walls, and then press the top or cover firmly to place, the inner or under surface of the top or cover being provided 90 with a depending central portion 14, corresponding with the raised portion 2 of the bottom or base and having a peripheral configuration corresponding with the plan of the in-

terior of the receptacle, or with beveled or cut-away corners 15, similar to those shown at 4. The edges of the sides and ends and the other flat abutting faces of the parts are wider than 5 the grooves and cover the same, and as the grooves all communicate with one another they can be filled with cement from a single point. Obviously these inwardly-extending flat-surfaced central portions of the base and 10 top constitute means for protecting the joints between the walls and said base and top and thereby prevent the cement, if applied in excessive quantities, from entering the vault, and also provide additional means for preventing communication of air to said interior. 15 An essential principle, however, of these inwardly-extending portions is to strengthen the points of connection of the top and base with the walls and give a stiffness to the 20 structure which is desirable without complicating the structure, as by braces or the equivalents thereof. In the same way the corner enlargements 7, which are carried by the ends of the side walls and bear at their 25 flat outer surfaces against the inner surfaces of the end walls, while their beveled inner surfaces bear against the beveled or chamfered corners of the base and top enlargements, further strengthen the structure at its 30 corners or at the joints between the side and end walls and coöperate with the inwardly-extending portions of the base and top to hold all of the parts in their proper relative positions without unnecessarily straining the cement keys by which the same are connected. 35

It has been my aim to provide a sectional vault or receptacle of which the parts are adapted to be manufactured and transported separately and to provide means for connecting 40 said parts, whereby when set up and closed the receptacle will be of equal strength with a receptacle of the same thickness of walls which has been molded in a single piece or as one block, and I have found in 45 practice that the inward projection of the central portions of the base and top, together with the terminal enlargements of the end walls, give a rigidity which enables the cemented joints to resist all strains due to the 50 ordinary uses of receptacles of this class.

In order to give additional strength to the structure, the side, bottom, and top walls are preferably provided with embedded metal bars 16, disposed longitudinally, and in order 55 to adapt the receptacle to perform the functions of a casket independently of any other receptacle I preferably embed tack-strips 17 in the inner surfaces of the side and end walls contiguous to their upper edges, the surfaces 60 of said strips being flush with the correspond-

ing surfaces of the walls and displacement of the strips being prevented by a dovetailed construction thereof, as will be seen by reference to Fig. 3. The draperies necessary for lining the interior walls of the receptacle may 65 be secured to these strips, and thus avoid the chipping of the material of the walls.

Looped handles 18 are provided in connection with the top or cover 13 to facilitate the lowering of the latter. 70

Various changes in the form, proportion, and the minor details of construction may be resorted to without departing from the spirit or sacrificing any of the advantages of this invention. 75

Having described my invention, what I claim is—

A receptacle of the class described, comprising a base provided with a flat-surfaced elevated central portion 2, and a depressed 80 edge portion 3 provided with a cement-groove of less width than the depressed surface, said elevated portion being cut away at the corners at 4, the side walls 5 having flat lower edges to fit the depressed portions 3 at opposite sides 85 of the central portion 2 and to cover the said groove, and having contiguous to their extremities the cross-sectionally-triangular inwardly-extending vertical enlargement 7 presenting angularly-disposed side faces fitting 90 the cut-away portions 4 of the base, said sides being flat between their extremities and the enlargement 7 and provided in such flat portions with grooves 9, the ends 6 seated against the flat end portions of the sides and the adjacent faces of the enlargement 7 and provided with vertical grooves 10 registering with the groove 9 and with the groove of the base, said sides and ends being provided at their upper edges with continuous grooves communicating with the vertical grooves 9 and 10, and the top or cover provided with the inwardly-extending central portion 14 cut away at the corners at 15 and fitting within the sides and ends and against the side faces of 105 the enlargement 7, said top or cover extending over the grooves of the upper edges of the sides and ends, and all the said grooves being adapted to be filled with cement from a single point and forming keys, when filled, 110 for holding the parts against lateral displacement, substantially as described.

In testimony that I claim the foregoing as my own I have hereto affixed my signature in the presence of two witnesses.

GIDEON G. OWEN.
